(57) **CLAIM**

The ornamental design for a touchless pointing device, as shown and described.

DESCRIPTION

FIG. 1 is a right, front, bottom-edge perspective view of a touchless pointing device showing the new design;

FIG. 2 is a left front, bottom-edge perspective view thereof;

FIG. 3 is a top-edge, back perspective view thereof;

FIG. 4 is a front view thereof;

FIG. 5 is a back view thereof;

FIG. 6 is a top-edge view thereof;

FIG. 7 is a bottom-edge view thereof; and,

FIG. 8 is a left side elevational view thereof, wherein the opposite right side view is substantially identical.
